COLLAPSIBLE CANINE KENNEL

Oliver H. Geib, Corunna, Mich.

Application May 10, 1946; Serial No. 668,936

1 Claim. (Cl. 20—2)

1

This invention relates to a collapsible canine kennel the main object of which is to provide a kennel that can be collapsed for the disinfecting and painting thereof as required.

Another object of the invention is to provide a kennel which in its collapsed or folded position can easily be carried by car to furnish a housing for the animal at any location wherever its owner may stop for lodging or the like.

Another object of the invention is to provide a kennel that is warm, wind and water proof and being raised from the ground there will be an air space below the floor thereof to maintain the floor dry under any type of weather.

With the above and other objects in view the invention consists of the novel details of construction, arrangement and combination of parts more fully hereinafter described, claimed and illustrated in the accompanying drawing in which:

Figure 1 is a front view of an embodiment of the invention;

Figure 2 is a side view thereof;

Figure 3 is a sectional view on the line 3—3 of Figure 2;

Figure 4 is a sectional view on the line 4—4 of Figure 1;

Figure 5 is a sectional view on the line 5—5 of Figure 1;

Figure 6 is a perspective view of one of the joints and

Figure 7 is a perspective view partly broken away of the floor brace.

Referring more in detail to the drawings the reference numeral 10 designates the kennel having ply wood side walls 12 having angularly cut top edges 14, and plywood front and rear walls 16 and 18 respectively, which are of a size to conform to the inclination of the top edge 14 of the side walls 12.

The front and rear walls 16 and 18 are secured to the vertical corner posts 20 by wood screws 22 on one face thereof inwardly of the longitudinal slots 24 in which the side walls 12 are removably received.

Secured to the front and rear walls by wood screws 26 adjacent the lower edge thereof are the floor supporting members 28 which are slotted at 30 to receive the marginal edge framing strips 32 secured to the undersurface of the floor 34. In like manner the floor supporting members 36 are secured to the side walls adjacent the lower edge thereof and are slotted at 38 to receive the strips 32 on the floor 34. At their engaging points

2

the members 28 are provided with tongues 40 to be received in the groove 42 in the members 36.

The members 36 are recessed at their medial point on the upper face thereof at 44 to receive the tongue 46 of the central floor brace 48 which is secured to the floor centrally thereof and the brace 48 is provided with a slide bolt 50 for engagement in an opening in the members 36 to retain the floor in position on the members 36 and 28.

The roof 52 has a frame 54 of the same size as the overall area of the upper edges of the walls secured to the undersurface thereof by wood screws 56 and the frame is slotted at 58 on the undersurface thereof to receive the upper edges of the walls. At the point of engagement with the top of the posts 20 the frame is cutout as at 60 to permit a tight fit of the roof on the walls.

Openings 62 are provided in the side of the frame 54 which are adapted to align with openings 64 in the side walls for the reception of removable headed pins 66 whereby the roof is secured to the walls and keepers 68 pivotally mounted on pins 70 in the frame engage the pins 66 to retain them in securing position.

A door frame 72 in the shape of a shield is secured to the front wall 16 by wood screws 74 and surrounds the doorway 76 formed therein. The frame is formed in half sections to receive the pivot rod 78 on which the door 80 is mounted and the door is cut shorter at its bottom 82 to allow a space thereunder through which the means for fastening the animal to the kennel may pass when the animal is inside the kennel. A metal plate 84 is secured to the door frame 72 at the bottom thereof to prevent damage to the frame by the fastening means for the animal.

A slide bolt 86 secured to the front wall in a position to engage the door 80 will retain the door in open position in good weather.

To erect the kennel the sides are placed on the ground in parallel position to each other with the members 36 on the inside thereof. The rear wall is then brought into position so that the tongue and groove joints of the members 28 and 36 will engage and the side walls enter the grooves 24 in the corner posts 20. Then the front wall is joined to the side walls in like manner. The floor is then dropped into place with the members 32 in the recesses 30 and the bolts are slid forward to retain the floor in place.

The roof is then placed on the walls, the pins 66 are inserted, the keepers 68 moved to retain the pins and the kennel is complete for the occupancy of the animal.

Thus a kennel has been provided that can be maintained in a sanitary condition at all times since it can be collapsed for the cleaning thereof and is easily collapsed for transportation purposes. The first roof permits the animal to lie thereon out of contact with the ground. The shape of the door retains the fastening means for the animal in the center thereof at all times and the short door permits ventilation of the kennel at the same time providing space for the fastening means.

It is believed that the construction of the kennel will be apparent to those skilled in the art and it is to be understood that changes in the minor details of construction, arrangement and combination of parts may be resorted to provided they fall within the spirit of the invention and the scope of the appended claim.

Having thus described the invention, what is claimed as new and desired to be secured by Letters Patent is:

A structure of the character described, comprising side, front and rear walls, vertically disposed posts secured along the side edges of the front and rear walls, grooves in said posts, removably receiving the edges of said walls to form a rectangular enclosure, a removable floor, horizontally disposed strips on said walls for supporting said floor, recesses in said horizontally

disposed strips at the wall side thereof, marginal edge framing strips on said floor received in said recesses to retain said rectangular enclosure in alinement at all sides thereof, a horizontally disposed brace on the undersurface of said floor parallel to the horizontally disposed strips on the front and rear walls, sliding bolts on said brace engageable in holes in the horizontally disposed strips on the side walls for retaining said floor in position, a removable roof and a rectangular frame on the under side of said roof having downwardly opening slots receiving the upper edges of said walls for retaining said roof in position.
